JULES LAGARDE, OF CLERMONT-FERRAND, FRANCE.

MACHINE FOR PRODUCING PERFORATED STRIPS FOR COMPOSING OR LIKE MACHINES.

SPECIFICATION forming part of Letters Patent No. 734,576, dated July 28, 1903.

Application filed October 29, 1902. Serial No. 129,232. (No model.)

To all whom it may concern:

Be it known that I, JULES LAGARDE, a citizen of the French Republic, residing at Clermont-Ferrand, in the Republic of France, 5 have invented certain new and useful Improvements in or Relating to Machines for Producing Perforated Strips for Composing or Like Machines, of which the following is a specification.

10 The present invention relates to a machine for perforating strips of paper in which groups or columns of perforations differing in the number and disposition of the perforations represent the letters of the alphabet or other 15 characters, the perforated strips being destined for actuating or controlling automatic composing or like machines.

An essential feature of the improved machine consists in the strips being not only provided with groups or columns of perforations, 20 but having also added to each group of perforations the printed mark of the letter or character represented by each group, whereby the verification or correction of the proof 25 during the composing is greatly facilitated.

In the accompanying drawings, Figure 1 is a rear elevation and partly in longitudinal vertical section of a machine according to this 30 invention. Fig. 2 is a plan view and partial horizontal section on the line A B C of Fig. 1. Fig. 3 is a side elevation and partial sectional view on the line C D of Fig. 1. Fig. 4 is a partial front view. Fig. 5 shows a portion of a perforated strip produced by the 35 machine, and Fig. 6 illustrates a modified constructional form of the punching device.

The machine rests upon a bottom plate 1, to which the different supporting parts are attached. Four of these supports, preferably 40 in the form of posts 2, carry a table or plate 3, on which two double electromagnets 4 4 are fixed by their cores. On the plate 3 and between the electromagnets 4 there is arranged a standard 5, to which is pivoted at 45 6 a balance-lever 7, carrying at its extremities hooks 8, provided with set-screws 9, the object of which will hereinafter be described. To both arms of the balance-lever 7 are linked connecting-rods 10, to the middle part of 50 which are pivotally connected levers 11, revolvably mounted at 12 in supports or standards 13, mounted on the plate 3, and provided

at their free ends with toothed segments 14, engaging one on either side of a common pinion 15, revolvably mounted at 16 in the standard 5 and in another standard 17, fixed to the plate 3.

The shaft 16 of the pinion 15 carries a disk 18, preferably made of insulating material, the circumference of which is provided with 60 a copper flange 19, on the circumference of which are arranged the different characters, letters, or other typographical signs.

Between its axis of oscillation 6 and the connecting-rods 10 the balance-lever 7 carries transverse arms 20, to which are fastened the extremities of armatures 21, the middle portions of which are provided with energizing-coils. These armatures coöperate with the upper poles of the electromagnets 4 4, and 70 the coils of the armatures are in circuit with the coils of the corresponding electromagnets.

At both sides of the plate 3 standards 22 are fixed to the bottom plate 1, to which standards are secured cross-bars 23, serving 75 as supports for a series of vertical electromagnets 24. Half-way up the standards 22 are other cross-bars 25, serving as supports for the cores of a series of horizontal electromagnets 24.

To each corner of the plate 3 are secured upwardly and downwardly extending arms or brackets 26 and 27, carrying the supports 28 and 29 for two other series of vertical and horizontal electromagnets 24, arranged in a 80 similar manner to the magnets 24 just referred to.

Between two opposite rows of magnets 24 are arranged standards 30, carrying rods or axles 31, on which are loosely mounted a series of three-armed levers 32. The two vertical arms of each lever form prolongations of each other, while the third arm is horizontally arranged. The upper ends of all the levers are all at exactly the same height, for 95 a purpose which will be hereinafter explained. Each lever 32 carries on one of its arms an armature 33, of soft iron, coöperating with its corresponding electromagnet 24. Some of the levers 32 therefore carry their armatures on their horizontal arms, while others have them fixed to their lower vertical arms. The electromagnets are arranged in two rows 100 on each side, and the two rows are so dis-

placed or break joint with regard to one another that the armature of a lever actuated by an electromagnet in the more remote row will not interfere or be interfered with by the adjacent electromagnet in the inner row. This arrangement enables a comparatively large number of independently-operating electromagnets to be arranged in a given space. The levers 32 are kept at equal distances apart by means of insulating-disks mounted on the axle 31.

Though alternately the horizontal and the lower vertical arms of the levers 32 are used as supports for the armatures, each lever 32 is, nevertheless, provided with three arms, in order to obtain a better balance, the horizontal arms serving to return the levers to their initial positions when the current is cut off. If desired, springs could be used for the latter purpose. In their initial positions the lower arms 32 lie against a cross-rod 82, fixed to the support 30.

Upon the bar 28, beyond each end of the balance-lever 7, are arranged bearings 34, carrying hinged to them the arms of stirrups or a frame 35, connected to a transverse bar 36, arranged above the upper ends of the vertical arms of the levers 32. The middle portion of the frame-bar 35, opposite to the bar 36, engages between a set-screw 9, carried by the balance-lever 7, and a hook 8 thereon, so that this frame or forked lever participates in the oscillating movement of the balance-lever 7, the necessary free space or play between the moving and the driven part being obtained by adjusting the set-screw 9.

Each bar 36 carries a series of adjustable screws 37, arranged in two rows and equal in number to the levers 32. The lower ends of these screws 37 are arranged at different heights above their corresponding levers 32, the distance between the lower end of each screw and the upper end of its corresponding lever 32 being adjustable. The upper end of each lever 32 is cut out or otherwise shaped in such manner that the screw 37 will not come in contact with the corresponding lever when the bar 36 is moved by the balance-lever 7 unless the lever 32 has been acted upon by its corresponding electromagnet 24. The lever 32 when operated by its electromagnet comes opposite the corresponding screw 37 and acts as a stop to the bar 36, determining thereby the amount of movement of the balance-lever 7.

All the screws 37 being arranged at different heights from the upper ends of the corresponding levers, each lever 32 when brought into action by its electromagnet will determine a different oscillation of the balance-lever 7. These oscillations of different angles are transmitted through connecting-rods 10, levers 11, and the toothed segments 14 to the pinion 15, which in turn rotates the disk 18 to a corresponding extent, which is there-

fore determined by the amplitude of the oscillation of one or other of the bars 35.

The mechanism connecting the balance-lever 7 to the segments 14 constitutes a kind of linked parallelogram, both segments acting at the same time, so that the pinion 15 may be rotated in one direction or the other, according as the electromagnet 24 in action is situated on the left-hand or on the right-hand side of the balance-lever 7.

Springs 38 of suitable strength are fixed to blocks of insulating material and operate upon the lower ends of the connecting-rods 10 to return the balance-lever 7 to its initial horizontal position after each oscillation. The free end of each spring 38 presses against a set-screw 39, so that by suitably adjusting the screws the initial position of the balance-lever 7 may be made exactly horizontal. At the end of each rotatory movement of the disk 18 the paper strip is perforated and then advanced. For this purpose the disk 18 is provided on its exterior circumference corresponding to the characters or signs engraved upon the ring 19 with a certain number of holes 40, which are arranged in this case in seven circumferential rows. A corresponding number of punches 41, formed on the extremities of levers 42, are arranged and are adapted to enter these holes. The levers 42, the number of which is here seven, in correspondence with the seven rows of holes upon the disk 18, are mounted on shaft 43, carried by a bracket 44, secured to the bottom plate 100 1. Each lever 42 is formed on its boss or hub with a projection or stop 45, abutting against a bar 46, fixed to the bracket 44 and maintaining all the levers 42 in a horizontal position.

The extremities of the levers 42 are provided on their under sides with recesses 47, constituting matrices, into which enter the pointed ends 48 of levers 49, loosely mounted upon a common shaft 50, fixed to the bracket 44, and corresponding in number and position with the levers 42. The levers 49 are also formed with projections 51 on the hubs resting against a bar 52, and thus serving to maintain the levers in a horizontal position 115 when the levers are not acted upon.

The strip 53 to be perforated passes between the two rows of levers 42 and 49.

Fig. 6 illustrates a modified construction of the punching mechanism, the lever 42 being provided instead of the matrix with a point 53, co-operating with a matrix 54, carried by lever 43. The section of this matrix is preferably enlarged toward the lower end. The modified construction of the punching mechanism facilitates the removal of the stamped-out bits of paper.

Transversely and underneath the levers 49 there is arranged a hammer 55, formed on the extremity of a lever 54, pivoted to the bracket 44. The surface of this hammer is coated, as may be best seen in Fig. 4, with india-rubber.

The hammer is provided with a lateral extension 56, also coated with india-rubber, adapted to come into contact with the periphery of the copper ring 19 of the disk 18 when the hammer is raised. The under side of the hammer 55 rests upon the extremity of a lever 57, pivoted at 58 to the bottom plate 1, the other extremity of the lever 57 being provided with a rounded head 59, against which 5 bears on each side one of the arms 60 of angle-levers pivoted to the bottom plate, the vertical arms 61 of which pass through and project above the plate 3 and are acted upon by transverse bars 62, oscillating in horizontal planes. The bars 62 carry attached to them electromagnets 63, coöperating with the lower poles of the electromagnets 4. A spring 64, bearing against the underside of the head 59 of the lever 57, causes the lever 61 and the bar 62 to resume their initial positions after the current has been interrupted.

As the object of the different parts above described is to record upon a strip of paper the matter to be composed by means of perforations and impressions, it is necessary to move the strip after each record corresponding to a character in order to enable another record to be made. This feeding movement of the strip is brought about in the following 25 manner: The lever 57 carries at its extremity adjacent to the hammer 55 a pin or projection 65, which when the hammer 55 returns to its initial position bears against an elastic spring 66 and depresses the spring into contact with another spring 67, whereby a circuit including a double electromagnet 68 is closed. This electromagnet attracts an armature 69 at the extremity of a lever 70, pivoted to a bracket 71 and carrying at its opposite end a spring-pawl 72. A spring 74 tends always to return the lever 70 to its initial position. Upon each rising movement of the pawl end of the lever 70 the pawl 72 operates a ratchet-wheel 73, the shaft of which 35 is mounted in bearings 75 and is integral with a roller 76, over which the paper strip 53 passes. A counter-roller 77, bearing against the strip, insures a perfect contact of the latter with the driving-roller 76. A set-screw 78 serves for adjusting the angle of oscillation of the lever 70, and consequently the 40 number of teeth by which the pawl 72 moves the ratchet-wheel, so that the feeding movement effected by the rollers 76 and 77 may be 45 regulated as desired.

In order to obtain simultaneously with the perforations a printed mark of the character upon the edge of the strip, two inking-rollers 79 are placed on opposite sides of the metallic 50 ring 19 and are mounted on pivoted levers 80, provided with counterweights 81 or appropriate springs.

The series of electromagnets 24 of the machine are electrically connected with corresponding parts of any desired system of keyboard or any other suitable apparatus—such

as, for instance, is described in my former application, Serial No. 69,950, filed July 27, 1901.

The electrical connection of the various coils of the apparatus is as follows: One end 70 of each coil 24 is connected to the corresponding part of the electric keyboard or other device—as, for instance, described in my said patent. The other ends of all the coils 24 situated on the same side of the apparatus 75 are connected to a single flexible wire leading to the two coils 4, arranged on the side of the machine opposite to the coils 24 in question. In the same manner the opposite coils 24 are connected with the two coils 4, 80 situated on the other side of the balance-lever 7. The return-wires of the coils 4 are connected to a common return-conductor. The coils of the armature 21 and the electromagnets 63, fixed to the bar 62, are contained 85 in the same circuit as the electromagnets 4, so that the current energizing the stopping-electromagnets 24 energizes at the same time the armature 21 and the coil 63. It is obvious from the foregoing description that when 90 the operator touches with the stylus one of the blocks of the board or operates one of the keys of the keyboard an electric current is sent into the corresponding electromagnet 24, which attracts the armature 33, situated in 95 front of it, and thus places the upper end of the corresponding lever 32 in the part of the transverse bar 36. The current passing at the same time through the two coils 4, situated on the other side of the balance-lever 7, will attract the corresponding armature 21, and thus 100 oscillate the balance-lever and move the transverse bar 36 in opposite directions. That one of the bars 36 which is situated on the same side as the lever 32 brought into action presses 105 against this lever with its corresponding screw 37 and determines thereby the amount of movement imparted to the balance-lever 7, which movement, as above described, is transmitted to the disk 18, as shown in Fig. 4. 110

The double electromagnet 4 through which the current flows attracts by the lower end of its core the bar 62, carrying the coils 63, whereupon the lever 57 is moved through the intermediary angle-lever 61. This movement 115 brings about an instantaneous upward movement of the hammer 55, which lifts all the points 84 against the strip 53. Those of the points which are stopped in their upward movement by the matrices 47 will perforate 120 the strip 53, so that the number and the position of the perforations are determined by the levers which are stopped in their upward movement.

As above described, the perforations and 125 the impressions are obtained by the action of the current actuating simultaneously the electromagnets 24, 4, 21, and 63, the disk being stopped in the proper position by the contact of the balance-lever with the lever 32, 130 corresponding to the character chosen, before the hammer 55 has accomplished its move-

ment. It is obvious, however, that instead of the disk and the hammer moving simultaneously a successive movement of the two parts in question could be easily obtained, 5 for instance, by arranging a contact device upon the bar 62, by which the circuit of an electromagnet arranged under the extremity 59 of the lever 57 would be closed. It has been already mentioned above that the disk 18 is provided on its whole periphery with a 10 number of holes arranged in seven circular rows corresponding with the seven levers 42. If, for instance, the disk 18 presents at the end of its rotatory movement four holes lying 15 in the same line transversely to the seven rows, these four holes coincide with the points of the levers 42 and enable, therefore, four of these levers to move upward, while the other three levers are maintained in position 20 and serve as matrices for the punches 48, so that three holes will be made in the strip transversely to the length of the strip. Besides the action of the hammer 55 on the levers 42 and 49 a mark or record of the character 25 corresponding with the group of perforations will be obtained by the coöperation of the projection 56 with the ring 19 of the disk 18. It will be easily understood that by the arrangement of different groups of perforations containing different numbers of holes arranged in a different way a great number 30 of different characters may be obtained. The strips thus perforated by means of the machine above described may be used for controlling or actuating machines serving for direct or telegraphic typographic composition.

What I claim as my invention, and desire to secure by Letters Patent, is—

1. A machine for producing perforated 40 strips for composing and like machines comprising a keyboard for actuating electrically the various corresponding parts of the perforating-machine, a wheel having a printing and a matrix surface, a series of punches and 45 dies and a presser all adapted to coöperate to produce a strip having, besides the ordinary perforations in determined combinations, the impressions of the letter or character corresponding to each group of perforations, for 50 the purpose of facilitating the verification and the correction of the strip by means of these marks or signs during the composing operation, the perforations and the production of the impressions being effected simultaneously 55 substantially as described.

2. In a perforating-machine of the kind described a series of electromagnets 24 corresponding in number with the signs or characters to be reproduced, and in electric connection with the blocks of the actuating apparatus (keyboard or the like,) and arranged symmetrically with regard to the axis of the machine; each electromagnet corresponding with an oscillating lever which when 60 brought into action determines the amplitude of oscillation of one of two bars each of which carries adjustable contacts all at different

levels and which are adapted to come in contact with corresponding levers such as 32 the said bars being operated by a balance-lever 70 actuated by electromagnets arranged in the circuit of the magnets 24 corresponding with the characters or signs, in such manner that the balance-lever oscillates in one or the other direction according to the character selected 75 and the electromagnet actuated and communicates its movement to a rotary disk which presents to the punching mechanism the groups of perforations arranged on its circumference and representing the different characters or signs in an inverse arrangement, that is the holes on the disk corresponding with full portions of the strips and vice versa; the disk being moreover provided with a flange carrying the letters or characters to be 80 printed at the same time as the perforations are effected, and corresponding each with its group of perforations substantially as described.

3. In a machine of the kind described the 90 combination of a disk of punches and corresponding matrices serving for perforating the composing-strip and actuated when the disk is stopped, by means of electromagnets arranged in the circuit and carried by a lever 95 acting upon, by means of intermediate levers, a hammer on the head of which rests the punch which punch when raised by the hammer strikes against the matrix and perforates the strip arranged between the said punch 100 and the matrix; the perforations produced presenting an inverse arrangement to the columns or groups on the disk; inasmuch as the full portions of the disk correspond with holes in the strip which latter are produced by 105 punches not corresponding with the holes in the disk; the matrices which are allowed to rise with their heads into engagement with holes in the disk producing no perforations, while on the contrary the matrices the heads 110 of which strike against full portions of the disk are reactive and coöperate with the punches to produce perforations; the feeding of the strip after each perforating operation being 115 preferably effected automatically by an electromagnet arranged in a separate electrical circuit and actuating a pawl-and-ratchet mechanism driving the strip-feed rollers substantially as described.

4. In a machine of the kind described a 120 balance-lever having depending arms actuating a matrix and printing-wheel through suitable gearing, pivoted levers at the ends of the balance-lever and engaging therewith and carrying at their outer ends a series of 125 projections each at a different height substantially as and for the purpose described.

5. In a perforating-machine of the kind described, a series of electromagnets 24 corresponding in number with the signs or characters to be reproduced, and in electric connection with the blocks of the actuating apparatus and arranged symmetrically with regard to the axis of the machine, oscillating 130

levers corresponding with each electromagnet, three-arm pivoted levers 32, each having an armature, a balance-lever, bars carrying contacts adapted to come into contact with the levers 32 and operated by the balance-lever, electromagnets in circuit with the magnets 24, and adapted to actuate the balance-lever, a rotatory matrix and printing-wheel and connections between the latter and the

balance-lever all adapted to coöperate in the manner and for the purpose specified.

In testimony whereof I have signed my name to this specification in the presence of two subscribing witnesses.

JULES LAGARDE.
